TOY BOAT OR GLIDER

William H. Paul, Highland Park, Ill.

Application July 31, 1940, Serial No. 348,885

7 Claims. (Cl. 46—93)

This invention relates to toys, and more particularly to toys of the class of boats, gliders and the like.

It is an object of the invention to provide a toy boat and glider structure of improved and simplified construction.

It is a further object of the invention to provide a structure of the type stated which may be readily fabricated and assembled and which more specifically may be collapsed for transport, shipment, or the like, and readily assembled when desired for use.

A still further object of the invention is to provide a toy boat and glider construction of universal character usable on land, ice, or in the water.

Another object is to provide a toy boat of the type stated which is operable in character, and to that end the invention contemplates the proportioning and arrangement of the structural parts in such a manner that the structure is self-operable and controllable when placed on or in a suitable supporting surface or medium, and when subjected to the propelling action of the wind.

Various additional objects, advantages, and features of the invention will be apparent from the following specification when taken in connection with the accompanying drawings wherein certain preferred embodiments of the invention are set forth for purposes of illustration.

In the drawings, wherein like reference numerals refer to like parts throughout:

Fig. 1 is a general assembly perspective view of a toy boat and glider constructed in accordance with one preferred form of the invention.

Fig. 2 is a perspective view of the structure of Fig. 1, but showing the same in collapsed condition as for transport, shipment, or the like.

Fig. 3 is a partial detail on an enlarged scale of the upper mast construction and associated parts.

Fig. 4 is a transverse sectional view through the construction of Fig. 1 on the line 4—4 thereof.

Fig. 5 is a vertical sectional view of the structure on the line 5—5 of Fig. 1.

Fig. 6 is a detail of one of the pontoons or support elements, and showing the same when conditioned for operation upon ice.

Fig. 7 is a sectional view through the structure of Fig. 6 on the line 7—7 thereof.

Fig. 8 is a detail view of a support element of a modified type, and particularly adapted for ice operation, and

Fig. 9 is a sectional view through the element of Fig. 8 on the line 9—9 thereof.

Referring more particularly to the drawings, and first to Fig. 1 thereof, it will be seen that the structure in general comprises a body 10 formed of a main longitudinal frame member 11 and a cross frame member 12, a mast 13, jib and main sails 14 and 15, and a series of supporting elements 16, 17 and 18 of universal character and adapted to support the structure on land, ice or water, as will later be more particularly described.

More specifically, the longitudinal frame member 11 forms the support for the mast 13 and to that end is provided with a recess or opening 20 as best shown in Figs. 1, 2 and 5, in which the lower end 13a of the mast is loosely pivotally received. The mast 13 which, like the frame members 11 and 12 is preferably of wood, carries an eye-screw 21 at its upper end forming the anchorage for the jib-sail support cord or forestay 22 and for a pair of mast support cords or stays 23 and 24. The cords 23 and 24 are secured at their upper ends to the eye-screw 21, and at their lower ends carry rings 25 and 26 respectively, Fig. 4, adapted to be removably associated with a pair of hook screws 27 and 28 anchored to the cross frame member 12.

The upper end of the jib-sail 14 is folded over as indicated at 14a, Fig. 3, and sewed or otherwise secured whereby to form a loop anchorage for the forestay cord 22, and the lower edge of the jib-sail is also folded over and sewed to form a tubular receiving pocket for a jib-boom member 30, Fig. 5. The pocket is closed at its forward end by folding over and sewing the sail cloth as indicated at 14b whereby to prevent the jib-boom from sliding forwardly from the pocket, and the forward end of the boom carries an eye-screw 31 connected to an eye-screw 32 anchored in the forward end of the longitudinal frame member 11. The rear end of the jib-boom 30 carries an eye-screw 33 to which one end of the jib-sheet cord 34 is connected, the cord being led through the loop of an eye-screw 35 and removably tied at its other end to a cleat 36. The cleat is carried upon a support platform 37 in turn suitably mounted upon the main longitudinal frame member 11, by suitable means such as screws or the like.

The main sail 15 is secured to the mast 13 by means of sewing its forward edge to form a tubular mast-receiving pocket, the upper end of the pocket being closed by sewing over the sail cloth as indicated at 15a, Fig. 3, whereby to prevent

the sail from sliding vertically downward with respect to the mast. The lower edge of the main sail is also folded over and sewed to form a tubular pocket to receive and support a main sail-boom 40, similar to the arrangement described in reference to the jib-sail construction. The forward end of the main sail-boom carries a yoke-screw 41, the bifurcated arms of which are adapted to embrace the mast 13, and the boom adjacent its rear end carries an eye-screw 42 to which one end of the main sail-sheet or control cord 43 is adapted to be adjustably secured or tied. The other end of cord 43 is secured to the rear end of a pivoted tiller bar 44.

The construction of the tiller bar and associated parts will be best understood from Figs. 1 and 4. More specifically, the tiller is provided with a depending shank portion 44a formed at its lower end 44b as a screw and thereby anchored in the support element 18. Shank 44a is loosely journaled in the frame member 11, and is provided with a collar 45 adapted to engage the upper face of member 11 whereby to prevent relative axial motion between the parts. A light torsion spring 46 anchored at its lower end 46a to the frame member 11 and at its upper end 46b to the tiller, serves normally to hold the tiller and the support element 18 in the position shown in Figs. 1 and 4. However, it will be seen that as the cord 43 is pulled in one direction or the other by the movement of the main sail-boom, pivotal motion is imparted to the tiller and the support element 18 secured thereto, the parts rotating with respect to the frame 11 by reason of the journal connection therewith previously described.

As shown in Figs. 1 to 6 inclusive, the support elements 16, 17 and 18 are in the form of pontoons and are preferably constructed of some light wood such as balsam wood or the like. Element 18 is secured in position by the means previously described. Elements 16 and 17 are provided with transverse recesses adapted to receive the ends of the cross frame member 12, the elements being secured to the frame member by suitable means such as screws 50 and 51, Fig. 4. The frame members 11 and 12 are removably secured together by a bolt 52, Figs. 1 and 5, and an associated wing nut 53, the frame members being provided with cooperating recesses or cut-away portions 11a and 12a, Fig. 2, so that they may be firmly locked in position and held against relative rotation by means of the bolt and wing nut when in the assembled position shown in Figs. 1 and 5.

The support elements or pontoons 16, 17 and 18 render the toy usable as a boat in water, and additionally suitable means is adapted to be replaceably associated therewith to render the construction usable on land and ice as well. To this end, as best shown in Figs. 4 and 5, the pontoons are provided with longitudinally extending slots 16a, 17a and 18a respectively in which wheels or rollers 55, 56 and 57 are adapted to be mounted by suitable support axles such as pins 58, 59 and 60. Preferably the axles are of brass or the like to preclude rusting if the wheels are left in the pontoons when the toy is used in water. Also, the wheels preferably are supplied with brass bearings, for example as indicated at 55a, Fig. 4, for support on the axles. The wheels render the toy usable as a land glider. The pins 58, 59 and 60, while normally fitting sufficiently tightly within the pontoons so as to prevent inadvertent separation of the parts, may be 75

pushed axially by the application of manual force whereby to permit the removal of the wheels and the substitution of sheet metal ice runners such as indicated at 61 in Figs. 6 and 7. By this means the toy is adapted for use as an ice boat.

The parts are so constructed and arranged as to render the toy operable as a boat or glider, as the case may be, when subjected to the propelling force of the wind. In an illustrative embodiment the longitudinal frame member 11 may be on the order of twenty-six inches in length, the cross frame member 12 may be on the order of fourteen inches in length and the mast 13 may be on the order of twenty-seven inches in length, the other parts being substantially in the proportion illustrated by the drawings. It is to be understood, however, that the size of the structure may be varied, preserving these relative proportions, or the proportions may be otherwise varied, if desired. The frame members 11 and 12 and the mast 13, as well as the booms 30 and 40, are preferably of wood so as to render the structure of relatively light weight, the support platform 31 lending sufficient mass to the body so as to stabilize the construction and prevent it from tipping in ordinary winds. With the parts so constructed and arranged, when the toy is subjected to the propelling force of the wind it is operably movable as a boat or glider when supported on or in a suitable medium. For use in water the pontoons 16, 17 and 18 alone will act as the support means. On land the wheels 55, 56 and 57 may be applied, and on ice the runners such as the runners 61 may be substituted. The position of the jib-sail 14 may be adjusted, if desired, by the adjustable connection between the control cord or string 34 and the cleat 36. Similarly, the permissible range of movement of the main sail 15 may be adjusted by reason of the adjustable connection between the control cord or string 43 and the eye-screw 42. Additionally as the main sail is stressed by the wind, the cord 43 tends to rotate the tiller 44 and the associated support element 18 against the action of spring 46 whereby to hold the structure into the wind. By this means actual tacking into the wind, within reasonable limits, may be accomplished. Normally the spring 46 yieldingly holds the support element 18 in the position shown in Fig. 1.

A further and important feature of the invention is the facility with which the structure may be collapsed as for transport, packaging, or shipment and reassembled as may be desired for use. To this end, referring to Figs. 4 and 5, it will be seen that merely by loosening the wing nut 53 and by disassociating the rings 25 and 26 from the hook screws 27 and 28, and by removing the mast 13 from its support socket 20, the structure may be collapsed into the compact arrangement illustrated in Fig. 2. More particularly, as the wing nut 53 is loosened, the two support frame members 11 and 12 may be vertically shifted and relatively rotated into the position shown in Fig. 2. The removal of the rings 25 and 26 from the hooks 27 and 28 permits this motion, and also permits the removal of the mast 13 from its support pocket 20. As the mast structure is collapsed, the yoke-screw 41 permits the main sail boom to be readily disassociated from the mast. The jib-boom support hooks 31 and 32 are also relatively pivotable to permit such relative movement as may be required. For the most part, however, the various support cords remain tied in position so that the parts will not become disas-

sociated and may be again assembled in the position shown in Fig. 1 by the repositioning of the three or four elements mentioned.

In Figs. 8 and 9 an arrangement is illustrated wherein the support elements such as the illustrated element 16a are smaller than the support elements as shown in Fig. 1, so as not to act as pontoons, and the ground contacting member associated therewith, such as the ice runner 61a, is permanently associated with the support element by rivets such as indicated at 65 and 66. In this form of construction the structure would be adapted for water or land use by the substitution of pontoons, or support elements having permanently associated wheels, by removal of the screws, previously described, such as illustrated at 50. In other words, in the construction of Figs. 8 and 9 the support elements themselves may be substituted with respect to the frame to adapt the toy for various types of supporting surfaces or mediums.

It is obvious that various changes may be made in the specific embodiments set forth without departing from the spirit of the invention. The invention is accordingly not to be limited to the specific embodiments shown and described, but only as indicated in the following claims.

The invention is hereby claimed as follows:

1. A toy of the class described comprising a toy body, a sail carried by the body and arranged in superposed relation with respect thereto, a series of pontoons carried by the body for supporting the same in a liquid medium, said pontoons being in individual spaced relation and lying substantially within a common plane, and individual ground engagement elements adjacent each of said pontoons and projecting below the lower surfaces thereof whereby to engage the ground when the toy is placed upon a solid medium.

2. A toy of the class described comprising a toy body, a sail carried by the body and arranged in superposed relation with respect thereto, a series of pontoons carried by the body for supporting the same in a liquid medium, said pontoons being in individual spaced relation and being disposed in a substantially common plane, and a wheel carried by each pontoon whereby the toy may be propelled along the surface of the ground when subjected to a suitable propelling force.

3. A toy of the class described comprising a toy body, a sail carried by the body and arranged in superposed relation with respect thereto, a series of pontoons carried by the body for supporting the same in a liquid medium, said pontoons being in individual spaced relation and being disposed in a substantially common plane, and an ice runner carried by each of the pontoons whereby the toy may be propelled along an ice surface when subjected to a suitable propelling force.

4. A toy of the class described comprising a toy body, a sail carried by the body and arranged in superposed relation with respect thereto, a series of pontoons carried by the body for supporting the same in a liquid medium, said pontoons being in individual spaced relation and being disposed in a substantially common plane, and a plurality of ground contacting devices adapted to be interchangeably secured to the pontoons adjacent the lower pontoon supporting surfaces thereof.

5. A structure as defined in claim 1, wherein said body comprises an elongated longitudinally extending frame member and an elongated transversely extending frame member secured in relatively immovable relation thereto to provide a T frame structure, said pontoons being carried adjacent either end of said transverse frame member and adjacent the rear end of the longitudinal frame member.

6. A structure as defined in claim 2, wherein said body comprises an elongated longitudinally extending frame member and an elongated transversely extending frame member secured in relatively immovable relation thereto to provide a T frame structure, said pontoons being carried adjacent either end of said transverse frame member and adjacent the rear end of the longitudinal frame member.

7. A structure as defined in claim 4, wherein said body comprises an elongated longitudinally extending frame member and an elongated transversely extending frame member secured in relatively immovable relation thereto to provide a T frame structure, said pontoons being carried adjacent either end of said transverse frame member and adjacent the rear end of the longitudinal frame member.

WILLIAM H. PAULL.
